UNITED STATES PATENT OFFICE.

ARTHUR W. MUELLER, OF CINCINNATI, OHIO.

PRINTING MECHANISM.

1,218,105.

Specification of Letters Patent. Patented Mar. 6, 1917.

Application filed December 14, 1914. Serial No. 877,107.

To all whom it may concern:

Be it known that I, ARTHUR W. MUELLER, a citizen of the United States, residing at Cincinnati, in the county of Hamilton and State of Ohio, have invented certain new and useful Improvements in Printing Mechanisms, of which the following is a specification.

My invention relates to printing mechanism especially applicable for printing the amounts in checks and other commercial paper and for similar purposes.

It is the object of my invention to provide novel means whereby the matter to be printed is readily placed in proper position for printing; further to provide means whereby the desired printing matter is placed in proper position for printing and a designation of said printing matter, movable with said printing matter, is shown; further to provide novel means whereby the paper to be printed is guided into printing position; further to provide novel means whereby the printed paper is ejected; further to provide novel means for printing the paper; further to provide novel connected means for printing the paper and ejecting the same after being printed; further to provide novel means for inking the surface from which the printing impression is taken; further to provide novel combined means for impressing the paper upon the printing surface and for inking the printing surface; further to provide a novel arrangement of the lines and columns designating the amounts; further to provide a movable support having printing lines for the amounts on one side thereof and lines of designations of said amounts at the other side thereof; further to provide an exposure-slot for said designations for exposing the designating line corresponding to the printing line placed in printing position; further to provide supports of the character mentioned side by side and movable in right lines for selective groupings thereof; and the invention will be further readily understood from the following description and claims, and from the drawings, in which latter:

Figure 1 is a plan view of my improved device, showing the printing supports in dash and zero printing positions.

Fig. 2 is a cross-section of the same on the line 2—2 of Fig. 1.

Fig. 3 is an enlarged detail on the line

3—3 of Fig. 6, showing the coacting faces between the printing surface and the coacting roller, and showing a strip of paper therebetween.

Fig. 4 is a plan view of a paper, partly broken away, representing for instance a part of a check, on which an impressed line made by my improved device is shown.

Fig. 4^a is a bottom view of a portion of the printing surface.

Fig. 5 is a plan view of my improved device with the cover and the indicator-caps for the slide-stems removed, and the printing supports in the nine and ninety printing positions.

Fig. 6 is a vertical section of the same on the line 6—6 of Fig. 5, showing the roller-carriage in full lines and the operating rod for the same partly broken away.

Fig. 7 is a detail of the same in vertical section on the line 7—7 of Fig. 5.

Fig. 8 is a perspective view of my improved device, with the printing supports and guide-rods and parts thereabove removed, and the plates between which the paper is received partly broken away, for better illustration of parts.

Fig. 9 is a right side elevation of my improved device.

Fig. 10 is a left side elevation of the same, partly broken away for showing the side gage in full lines in position for engaging a narrow paper, and in dotted lines for engaging a wide paper.

Fig. 11 is a bottom view of the printing supports arranged in columns with the corresponding digits of the respective columns in cross line.

Fig. 12 is a perspective view of one of the larger printing supports or slides, depicting the same on the guide-rods.

Fig. 13 is a perspective view of one of the smaller printing supports or slides, mounted on a single rod.

Fig. 14 is a vertical longitudinal section of one of the smaller slides, taken on the line 14—14 of Fig. 13.

Fig. 15 is a detail in plan view showing the roller carriage mounted on its guide-way, with the impression roller in impressing position.

Fig. 16 is a vertical cross-section of the same on the line 16—16 of Fig. 15, and showing the printing support.

Fig. 17 is a cross-section showing the 110

roller-carriage in coacting position with the printing support, and taken on the irregular line 17—17 of Fig. 20.

Fig. 18 is a detail in vertical section taken on the line 18—18 of Fig. 16, showing the roller-carriage adjacent to the end of its printing travel, showing the impressing roller in impressing position and the inking roller in ink-receiving position.

Fig. 19 is a similar view, showing the roller-carriage at the end of its printing travel with the rollers held in normal positions by the spring acting on the roller-carriage.

Fig. 20 is a vertical section of the roller-carriage shown in inking and check-ejecting relation and taken on a line corresponding to the line 20—20 of Fig. 17.

Fig. 21 is a top plan view, partly broken away, showing the means for positioning the larger slides.

Fig. 22 is a cross-section of the same on the line 22—22 of Fig. 21.

Fig. 23 is a side elevation of the same, the slide-bars being partly broken away.

21 represents the case, which comprises a body 22 having a removable top 23. The body has an extension 24 at its right and an extension 25 at its left.

30 A series of movable supports are provided, on which are columns, instanced as of lines of characters to be printed representing amounts. The supports are relatively shiftably so as to be capable of being 95 adjusted into new relations for representing the sums which are the resultant of the several numbers represented in the lines of the respective columns arranged side by side, there being preferably columns representing dollars, and columns representing cents.

Thus 31, 32, are the supports representing the cents, and 33, 34, 35, 36 and 37, are the supports representing the dollars, a 45 suitable number of these supports being employed, depending on the sum total it is desired to print by means of my improved device.

In the present exemplification, the movable support 31 represents the cent values, shown by printing lines 311; the movable support 32 the dime values, shown by printing lines 321; the movable support 33 unit and teen dollar values, shown by printing lines 331; the movable support 34 the tens of dollar values above ten, shown by printing lines 341; the movable support 35 the unit hundred dollar values, shown by printing lines 351; the movable support 36 the unit and teen thousand dollar values, shown by printing lines 361; and the movable support 37 the ten thousand dollar values above ten thousand, shown by printing lines 371. Each of the dollar movable supports has 65 a zero or dash printing line in its column,

shown at the head of the column, as at 332, 342, 352, 362 and 372, and the unit and teen thousand dollar support has a line representing "thousand," shown at 36^a, for coaction with the representations of the amounts on the movable support 37.

The movable supports are shown as slides, the movable supports 31, 32, respectively slidably on guides 38, and the supports 33 to 37 inclusive respectively slidably on 75 guides 39, 40, the guides being shown as rods which are suitably rigidly secured in the case as by means of screws 41, securing the ends of said bars to ledges 42 formed as part of the case. The printing lines are 80 shown presented downwardly.

In the present exemplification the movable supports are also shown as having designating surfaces 44 on which the counterparts of the printing lines and columns are 85 shown, the respective lines of the designating surfaces of the respective supports being arranged to be placed in registry with an exposure-slot 43.

The designating lines on the respective 90 supports are shown at 313, 323, 333, 343, 353, 363 and 373.

In the present exemplification the designating surfaces are at the tops of the supports, corresponding lines in the various 95 printing columns and designating columns being placed opposite each other on the supports, so that when a given designating line is placed at the exposure-slot the corresponding printing line will be in printing 100 position. Thus in Fig. 1 the dash and zero lines of the designating columns are in registry with the exposure-slot, the dash and zero printing lines being in printing position immediately therebelow.

105 The movable supports are provided with stems 45 for shifting the same. These stems project through slots 46 in the top of the case and are provided with removable caps 47 having indicator-fingers 48 110 thereon which are arranged to register with the respective lines 314, 324, 334, 344, 354, 364 and 374 of indicating columns shown stationarily located on the top of the case. The numbers in the respective lines of the 115 indicating columns correspond to the numbers in the lines of the printing columns and of the designating columns, but are oppositely arranged. Thus referring to Fig. 1, in which the lower portion of the figure 120 represents the portion of the machine presented toward the operator, the numbers in the indicating columns increase away from the operator's position, whereas the numbers in the printing and designating columns 125 increase toward the operator's position, as will be seen in Figs. 11 and 5.

130 It will be noted that in the arrangement of the columns, those columns which embrace the teens of dollars and thousands of

dollars are longer than the other columns, the teens parts of the columns normally extending beyond the range of the other columns, as shown in Figs. 5 and 11. For 5 accommodating the range of movements of these longer columns, the slots for the shifting stems 45 thereof extend to the other side of the exposure-slot, as shown at 46' in Fig. 1, the slots 46 being preferably at 10 one side of said exposure-slot.

An example of the paper to be printed is shown at 51. The paper is arranged to be inserted in a slot 52 in the side 53 of the case above the ledge 54 of the extension 24, against a side-gage 55 and an end-gage 56, and between lower supporting plates 57, 58, and upper plates 59, 60. (See Fig. 8). The supporting plates have paper-receiving spaces 61, 62, between them, in which the 20 paper to be printed is arranged to be received.

The proximate ends of the plates have a space 63 between them, in which the impression roller and the inking roller herein- 25 after described are arranged to be received for making contact with the paper and printing lines respectively. The plates 57, 58, and 59, 60, are suitably rigidly secured to the case.

30 The end-gage 56 is on a bar 66 provided with a slot 67 and having a lug 68 thereon by which the gage may be pushed endwise for positioning the same, a clamp-screw 69 being received through the slot 67 and threaded into the top 70 of the extension 25. A pin 71 secured to said top 70 and received through the slot 67 aids in maintaining the longitudinal position of the end-gage.

40 The side-gage 55 extends from side to side of the case between the plates 57, 59. It is provided with depending ends 74 extending lengthwise of the sides of the case and provided with slots 75. One of the 45 walls of each of the slots is provided with a tooth-rack 76, pinions 77 coacting with these tooth-racks, the pinions being fast on a shaft 78 journaled in bearings in the sides of said case and having a thumb-wheel 79 thereon for turning the same and thereby positioning the side-gage toward and from the line of travel of the impression roller so as to position the check, for instance, in proper position for placing the line thereof 55 to be printed in printing position.

The side-gage is arranged to be reversed so as to substantially double its range of adjustment for accommodating, for instance, so-called voucher-checks, if the machine is 60 desired for this purpose. The mounting of the side-gage for comparatively narrow paper, such as ordinary checks, is shown in full lines in Fig. 10, and its mounting for comparatively wide paper, such as voucher- 65 checks, is shown in full lines in Fig. 8, and

in dotted lines in Fig. 10. A voucher-check is shown in printing position in Fig. 8.

Means are provided for locating the slides so that their printing lines register in printing position. In the present exemplification 70 the slides are provided with longitudinal recesses, which in the narrower slides are designated 81 and in the wider slides are designated 82. The supporting guide-rods 38 and 39, 40, extend through these recesses. 75

The wider of the slides are each supported on a plurality of guide-rods. (See Figs. 1, 6, 12, 21, 22 and 23.) Springs 83 are located in the recesses 82 of these slides. One of the ends of each of these springs is rigidly secured to the slide, as by screws 84 extending into a lug 85 on said slide. The free ends of these springs have locating parts 86 thereon which coact with locating parts 87 on the guide-rods. The locating parts on the 80 springs are shown as fingers provided with inclined sides, the locating parts on the rods being shown as coacting notches. When the fingers are seated in the notches, which is readily indicated to the operator by the 85 resistance offered to movement of the slide, a printing line is in printing position.

But one spring is employed in connection with the narrower of the slides, (see Fig. 14), 90 in which a spring 88 is secured to the slide 95 at one end thereof by screws 89, the free end of the spring being provided with a positioning part 90 which coacts with the positioning parts 91 on the guide-rod.

10065 10070 10075 10080 10085 10090 10095 10100 10105 10110 10115 10120 10125 10130 10135 101

125 (see Fig. 3), with which projections 126 on the printing faces extending lengthwise of the printing lines coact, the projections on one of said parts being received in the 5 spaces between the projections on the other of said parts for impressing upon or breaking the paper being printed, as shown at 127 in Fig. 3, so as to impress or fix into the paper the forms of the letters or type being 10 impressed upon the paper.

The inking roller is shown in the form of a peripheral annular inking pad, which is moved across the face of the printing line for inking the same. The inking roller is 15 arranged to coact with a suitable ink-applying device, shown as an ink-pad 128.

The tracks 114 are formed with inwardly extending ledges extending toward each other, above and under which ledges the 20 axes of the impression roller and of the inking roller are arranged to ride. Novel means are provided for causing location of said axes above or below said ledges. For this purpose the lower faces of the ledges 25 are provided at their respective ends with upward inclines 129, 130, (see Fig. 6) which merge into comparatively thin extensions 131, 132, of said ledges.

At the ends of the paths of travel of said 30 carriage, the impression roller and inking roller are located in the same horizontal planes, in compartments 241, 251, of the extensions 24, 25, that is to say, the carriage-frame 104 is normally in horizontal position, being urged into this position by means of a spring 135 secured to the cross-bar 108, which is rigid with the yoke, and received in a slot 136 of the connecting strip 106, which is rigid with the carriage.

40 The normal position of this frame is shown in Fig. 19, which it will be assumed is about to be pushed in the direction of the arrow *a* on the inking and paper-ejecting trip of the carriage. The anti-friction rolls 45 122 will first strike the extension 132, causing the impression roller 102 to be partway depressed and causing the rise of the inking roller 103 to be initiated. When the anti-friction rolls 122 strike the inclines 130, a 50 further depression of the impression roller will take place, causing a further rise of the inking roller, for bringing its anti-friction rolls 124 level with the top of the track, so that these anti-friction rolls 124 will ride upon said track, so that when the carriage 55 is pushed across the machine in the direction of the arrow *a*, an inking of the line of type which is in range of the inking roller will take place.

60 The carriage adjacent to the inking roller is provided with upwardly extending fingers 138, respectively provided with notches 139, in which the edge of the paper 51 is arranged to be received when the notches reach 65 the left-hand end of the paper in the travel

of the carriage being pushed in the inking movement lengthwise of the printing line, whereby the paper is ejected from the machine between the plates 57, 58, and 59, 60. These fingers extend upwardly into the space 70 63 between the proximate ends of said plates. At the end of the paper-ejecting movement of the carriage, the anti-friction rolls 124 will pass off the ends of the extensions 131 and by the action of the spring 135 be depressed so as to return the carriage to normal level. 75

When the carriage is pulled, which in the present exemplification is the printing movement of the carriage, the anti-friction rolls 80 124 will first strike the lower faces of the extensions 131 for initiating a rise of the impression roller, and when said anti-friction rolls strike the inclines 129, the anti-friction rolls 122 will be raised to be received on the 85 tops of the tracks and will ride upon the tops of the tracks for causing impression by said rollers of the paper against the printing lines brought into the path of movement of the impression roller by the adjustment 90 of the slides hereinbefore described. When the anti-friction rollers 124 reach the ends of the ledges of the tracks, the carriage is returned to normal position by means of the spring 135. 95

In Fig. 18 the carriage is shown near the end of the printing movement, and in Fig. 20 the carriage is shown near the end of the inking and paper-ejecting movement, the directions of movement being indicated by 100 the arrows.

The caps 47 have releasable frictional engagement with the stems 45. The top 23 of the case has frictional engagement with the body of the case. When the caps 47 have 105 been slipped off the stems, the top is readily removable.

The line of the hundred dollar column and of the unit and teen thousand dollar column of printing lines respectively have the word 110 hundred and thousand, or abbreviation thereof, associated therewith, whereby sequence in the designation of the sum is readily provided.

My improved apparatus provides a flat 115 and compact device for the purpose intended, the arrangements of its sums being provided by longitudinal movements of its slides. It requires few movements for the arrangement and printing of a composite line and exposes 120 the designation of the composite line to be printed, prior to the printing thereof, so that error may be avoided, the sum being further verified by the positions of the indicator finger. 125

The arrangement of the teens of dollars and teens of thousands of dollars beyond the normal positions of the units and tens of the printing, designating and inking surfaces, facilitates the proper placement of the 130

printing lines in cross relation, and insures against error, and furthermore the location of the extensions 46' of the slots 46 for said teens values form separating devices between the cents columns and the dollar columns less than thousands and between the dollar columns less than thousands and the dollar columns greater than thousands for additionally insuring against error.

10 Having thus fully described my invention, what I claim as new and desire to secure by Letters Patent, is:

1. In a printing mechanism, in combination, a series of supports having printing lines at one side thereof and corresponding designating lines at the opposite side thereof, said supports arranged side by side and for relative longitudinal movement, guideways for said supports, and resiliently acting means between said guideways and supports located between said printing lines and designating lines which are on said opposite sides of said supports, said resiliently acting means acting resiliently in both directions of movement of said supports for causing cross alinement of the printing lines on said series of supports.

2. In a printing mechanism, the combination of a case provided with an exposure-slot, a printing means in said case, and a series of supports having printing lines at one side thereof for coaction with said printing means and designating lines at the opposite side thereof for coaction with said exposure-slot, said supports arranged side by side and for relative longitudinal movement, guideways for said supports, said exposure slot being of a width to expose solely a composite designating line composed of a designating line on each of said supports, and resilient means between said guideways and supports located between said printing lines and designating lines which are on said opposite sides of said support, said resilient means acting resiliently in both directions of movement on said supports for resiliently positioning said last-named designating lines in registry with said exposure slot.

3. In a printing mechanism, the combination of a case provided with an exposure-slot, slides in said case provided with printing lines presented downwardly and with corresponding designating lines presented upwardly, an indicating means comprising a pair of parts one of which consists of indicating lines and the other of which consists of indicating fingers, one of said parts having connection with said slides for movement thereof, an impressing device, means for causing relative cross-movement between said impressing device and said slides, and said slides arranged for relative longitudinal movement for presenting selective ones of said printing lines in cross-line coaction with said impressing device, corresponding selec-

tive ones of said designating means in registry with said exposure-slot and for denoting corresponding lines in said indicating means.

4. In a printing mechanism, the combination of a case, a series of slides therein provided with printing lines, a printing means for said slides, guide-rods on which said slides slide, and means for positioning said slides lengthwise of said guide-rods comprising springs secured to said slides, said springs and guide-rods provided with coacting means for locating said printing lines selectively in printing position, and means for causing cross-movement between said printing means and said series of slides for effecting the printing.

5. In a printing mechanism, the combination of a series of slides provided with printing lines and movable relatively longitudinally for cross-lining selective ones of said printing lines in printing position, a printing means comprising a rockable frame provided with an impressing means coacting with said printing lines and with an inking means coacting with said printing lines, means for rocking said rockable frame for causing selective coaction of said impressing means and said inking means with said printing lines, and means for causing cross-movement between said rockable frame and said series of slides.

6. In a printing mechanism the combination of slides having printing lines and arranged for relative longitudinal movement for selective cross-lining of said printing lines in printing position, and printing means comprising a rockable frame having an impressing roller and an inking roller, and tracks extending crosswise of said slides, means for causing cross-movement between said rockable frame and said slides, and a track having directing faces for coacting with said rockable frame for causing the mounting of the axes of said respective rollers relatively to said track for coaction with said printing lines in printing position respectively during opposite ones of said cross-movements.

7. In a printing mechanism, the combination of supports provided with printing lines, said supports arranged for relative longitudinal movement for selective cross-lining of said printing lines in printing position, printing and inking means, a track for said printing and inking means, means for causing cross-movement between said printing and inking means and said supports, and means for causing coaction of said printing and inking means with opposite sides of said track during reverse movements between said printing and inking means and said supports.

8. In a printing mechanism, the combination of supports provided with printing lines, said supports arranged for relative

- longitudinal movement for selective cross-lining of said printing lines in printing position, and a printing and inking means comprising a rockable frame, an impressing 5 roller and an inking roller on said rockable frame, means for causing cross-movement between said rockable frame and said first-named supports, a track, and coacting means for rocking said rockable frame for presenting the axes of rotation of said impressing roller and inking roller alternately at opposite sides of said track, and a spring for normally retracting said rockable frame from rocked position.
15. In a printing mechanism, the combination of a case, slides in said case provided with printing lines presented downwardly, a printing means, below said slides, said slides arranged for relative longitudinal 20 movement causing cross-registry of selective ones of said printing lines in printing position, paper-receiving means locating the paper to be printed between said slides and printing means, and means for causing relative cross-line movement between said printing means and said slides in a direction substantially parallel to the plane of said slides.
10. In a printing mechanism, the combination of a case provided with an exposure-slot, slides in said case provided with printing lines presented downwardly and with corresponding designating lines presented 30 upwardly, a printing means, said slides relatively movable longitudinally for causing cross-registry of selective printing and designating lines on said slides in positions coacting respectively with said printing means and said exposure-slot, and means for causing cross-movement between said printing 35 means and said slides in a direction substantially parallel to the plane of said slides for effecting the printing.
11. In a printing mechanism, the combination of an inclosing case, slides therein 45 provided with printing lines at one side thereof, said slides supported for relative longitudinal movement for causing cross-registry of selective ones of said printing lines, a printing means coacting with said printing lines, and means for causing cross-movement between said printing means and said slides in a direction substantially parallel to the plane of said slides for effecting the printing.
12. In a printing mechanism the combination of an inclosing case, slides therein provided with printing lines at one side thereof, said slides supported for relative right line movement for causing cross-registry of selective ones of said printing lines, a carriage 55 movable crosswise of said slides, impressing means and inking means on said carriage, means causing coaction between said impressing means and said selective ones of said printing lines during movement of said car-

riage in one direction, and means causing coaction between said inking means and said selective ones of said printing lines during movement of said carriage in the opposite direction.

13. In a printing mechanism, the combination of a case provided with an exposure-slot, slides in said case provided with printing lines presented downwardly and with corresponding designating lines presented upwardly, an indicating means comprising a pair of parts one of which consists of indicating lines and the other of which consists of indicating fingers, one of said parts having connection with said slides for movement therewith, and an impressing device movable crosswise of said slides, and said slides arranged for relative longitudinal right-line movement for presenting selective ones of said printing lines in cross-line coaction 85 with said impressing device, corresponding selective ones of said designating lines in registry with said exposure-slot and for denoting corresponding lines in said indicating means.

14. In a printing mechanism, the combination of a case provided with a removable top having an exposure-slot, slides in said case provided with printing lines presented downwardly and with designating lines presented upwardly, said slides arranged for relative longitudinal movement, said top provided with slots in line with the lines of said movement, means above said top having connection with said slides for moving the 105 same, and indicating gages extending lengthwise of said last-named slots with which said last-named means coact, said last-named means extending across the walls of said last-named slots and being removable, whereby said top is removable for exposure of said slides.

15. In a printing mechanism, the combination of a case, a series of slides therein provided with printing lines, a printing 110 means movable crosswise of said slides, guide-rods on which said slides slide, and means for positioning said slides lengthwise of said guide-rods comprising springs secured to said slides, said springs and guide-rods provided with coacting means for locating said printing lines selectively in printing position.

16. In a printing mechanism, the combination of a case, a slide provided with printing lines, an impressing device movable crosswise of said slide, a guide-rod on which said slide slides, and a spring secured to said slide and provided with a positioning part, said guide-rod provided with coacting 125 positioning parts, whereby said slide is positioned on said rod for selective location of said printing lines in the path of said impressing device.

17. In a printing mechanism, the combina- 130

tion of a case provided with a top having an exposure-slot, slides in said case provided with downwardly presented printing lines and upwardly presented corresponding designating lines, an impressing means movable crosswise of said slides below said slides, said slides arranged for selective longitudinal movement for locating selective ones of said printing lines in the path of said impressing means and corresponding selective ones of said designating lines in registry with said exposure-slot, and means for moving said slides extending through said top, and said top provided with slots at right angles to said exposure-slot at both sides of said exposure-slot in which said means for moving said slides travel.

18. In a printing mechanism, the combination of a case provided with an extension 20 at each side thereof, slides in said case arranged for relative longitudinal movement in said case, and impressing and inking means movable crosswise of said slides across said case and in said extensions.

25 19. In a printing mechanism, the combination of a case provided with a side-extension below the top of said case, slides provided with printing lines presented downwardly mounted for relative lengthwise 30 movement in said case above the level of said extension, and an impressing and inking means mounted for movement crosswise of said slides in said case and in said extension below the level of said slides.

35 20. In a printing mechanism, the combination of a case provided with a side-extension below the plane of the top of said case, slides provided with printing lines presented downwardly mounted for relative lengthwise movement in said case above the level of said extension, an impressing and inking means mounted for movement crosswise of said slides in said case and in said extension below the level of said slides, and 40 paper receiving means between said slides and said impressing and indicating means.

21. In a printing mechanism, the combination of a case provided with side-extensions, slides provided with downwardly presented printing lines arranged for relative longitudinal movement in said case, printing means comprising a rockable carriage and tracks below said slides extending crosswise of said slides, said tracks interrupted 50 approximately at said extensions, and means for rocking said carriage arranged whereby said carriage is in normal position when in said extensions and in rocked position when traveling between said extensions.

60 22. In a printing mechanism, the combination of a series of slides provided with printing lines and movable relatively longitudinally for cross-lining selective ones of said printing lines in printing position, 65 a printing means comprising a rockable car-

riage provided with an impressing means coating with said printing lines and with an inking means coating with said printing lines, and means for rocking said carriage for causing selective coaction of said 70 impressing means and said inking means with said printing lines.

23. In a printing mechanism, the combination of slides provided with downwardly presented printing lines, said slides arranged for relative longitudinal movement for causing selective arrangement of said printing lines in printing position, printing means comprising a rockable carriage movable crosswise of said slides and comprising 80 an impressing roller and an inking roller, and tracks for said carriage, said tracks provided with downwardly facing inclines at the respective ends thereof coating with said carriage for rocking the same and causing selective coaction between said impressing roller and said inking roller with said printing lines in printing position.

24. In a printing mechanism, the combination of slides having downwardly presented printing lines and arranged for relative longitudinal movement for selective cross-lining of said printing lines in printing position, and printing means comprising a rockable carriage having an impressing roller at one end thereof and an inking roller at the other end thereof, and tracks on which said carriage moves extending crosswise of said slides, said tracks at the respective ends thereof having downwardly 90 presented directing faces for directing that roller of said carriage which is in advance in either direction of movement of said carriage downwardly and causing the mounting of the axis of the following roller above 95 said tracks for coaction with said printing lines in printing position.

25. In a printing mechanism, the combination of a case provided with side-extensions, slides having downwardly presented 100 printing lines and arranged for relative longitudinal movement for selective cross-lining of said printing lines in printing position, and printing means comprising a rockable carriage having an impressing roller at one end thereof and an inking roller at the other end thereof, and tracks on which said carriage moves extending crosswise of said slides, said tracks at the respective ends thereof having downwardly presented 110 directing faces for directing that roller of said carriage which is in advance in either direction of movement of said carriage downwardly and causing the mounting of the axis of the following roller above 115 said tracks for coaction with said printing lines in printing position.

26. In a printing mechanism, the combination of a series of slides provided with printing lines and movable relatively longitudinally for cross-lining selective ones of said printing lines in printing position, and said carriage received in said side-extensions at the ends of its movements.

27. In a printing mechanism, the combination of a case provided with a top having an exposure-slot, slides in said case provided with downwardly presented printing lines and upwardly presented corresponding designating lines, an impressing means movable crosswise of said slides below said slides, said slides arranged for selective longitudinal movement for locating selective ones of said printing lines in the path of said impressing means and corresponding selective ones of said designating lines in registry with said exposure-slot, and means for moving said slides extending through said top, and said top provided with slots at right angles to said exposure-slot at both sides of said exposure-slot in which said means for moving said slides travel.

- nation of movable supports provided with downwardly presented printing lines, said supports movable longitudinally for selective cross-line positioning of said printing lines, a printing carriage movable crosswise of said supports, and paper-receiving means located between the planes of said supports and carriage, said carriage provided with paper-contacting means arranged to contact the edge of the paper for causing ejecting of said paper from said paper-receiving means upon crosswise movement of said carriage.
27. In a printing mechanism, the combination of supports provided with downwardly presented printing lines, said supports arranged for relative longitudinal movement for causing selective cross-line arrangements of said printing lines, a rockable carriage arranged for movement crosswise of said supports having an impressing means at one end thereof, an inking means at the other end thereof, and paper-contacting means whereby to contact the edge of the paper for causing its ejection.
28. In a printing mechanism, the combination of supports provided with downwardly presented printing lines, said supports arranged for relative longitudinal movement for selective cross-lining of said printing lines in printing position, and a printing and inking means comprising a rockable carriage, means for moving said carriage crosswise of said supports, and tracks on which said carriage is mounted, and coacting means between said tracks and carriage whereby said carriage is rocked for presenting the axes of said impressing roller and inking roller alternately above and below said tracks.
29. In a printing mechanism, the combination of supports provided with downwardly presented printing lines, said supports arranged for relative longitudinal movement for selective cross-lining of said printing lines in printing position, and a printing and inking means comprising a rockable carriage, an impressing roller and an inking roller on said carriage, means for moving said carriage crosswise of said supports, tracks on which said carriage is mounted, coacting means between said tracks and carriage whereby said carriage is rocked for presenting the axes of said impressing roller and inking roller alternately above and below said tracks, and a spring for normally retracting said carriage from rocked position.
30. In a printing mechanism, the combination of supports provided with downwardly presented printing lines, said supports arranged for relative longitudinal movement for selective cross-lining of said printing lines in printing position, and a printing and inking means comprising a rockable carriage and means for moving
- said carriage crosswise of said supports, an impressing roller and an inking roller, tracks on which said carriage is mounted having lateral ledges which guide said rollers, and coacting means between said lateral ledges and carriage whereby said carriage is rocked for presenting the axes of said impressing roller and inking roller alternately above and below said ledges, and a spring for normally retracting said carriage from rocking position.
31. In a printing mechanism, the combination of supports provided with downwardly presented printing lines, said supports arranged for relative longitudinal movement for selective cross-lining of said printing lines in printing position, and a printing and inking means comprising a rockable carriage, an impressing roller and an inking roller on said carriage, means for moving said carriage crosswise of said supports, tracks on which said carriage is mounted, coacting means between said tracks and carriage whereby said carriage is rocked for presenting the axes of said impressing roller and inking roller alternately above and below said tracks, and an inking pad at one end of the path of travel of said carriage for coaction with said inking roller.
32. In a printing mechanism, the combination of a case, a printing surface, superposed paper-receiving plates for locating the paper to be printed under said printing surface and a side-gage between said plates for said paper provided with means for adjusting said side-gage extending toward one side of said side-gage, and a stationarily positioned coacting adjusting means, said side-gage arranged for reversal of position thereof between said paper-receiving plates so that its said means for adjusting extend in the opposite direction for coacting with said stationarily positioned coacting means for substantially doubling its range of adjustment between said plates.
33. In a printing mechanism, the combination of a case provided with side-extensions below the top of said case, slides provided with downwardly presented printing lines arranged for relative longitudinal movement in said case above the planes of said extensions, printing means comprising a carriage and tracks below said slides extending crosswise of said slides, paper-receiving means between said slides and tracks, said side-extensions provided with tops, and an end-gage for the paper adjustable on one of said last-named tops and the other of said last-named tops serving as a paper-support.
34. In a printing mechanism, the combination of movable supports provided with downwardly presented printing lines, said supports movable longitudinally for selective cross-line positioning of said printing

lines, a printing carriage movable crosswise of said supports, and paper-receiving plates located between the planes of said supports and carriage having an interruption therein 5 in line with the path of movement of said carriage, said carriage provided with paper-contacting means arranged to contact the paper through said interruption.

35. In a printing mechanism, the combination of movable supports provided with printing lines arranged to be brought into selective cross-line arrangement by adjustment of said supports, said printing lines provided with projections and depressions 10 extending in lines lengthwise of said printing lines, an impressing roller provided with peripheral depressions and projections arranged to coact with said first-named projections and depressions, and means for 15 causing cross-movement between said impressing roller and said movable supports for causing coaction between said depressions and projections respectively on said printing lines and said impressing roller.

25 36. In a printing mechanism, the combination of movable supports respectively provided with printing lines arranged to be brought into selective cross-line arrangement by adjustment of said supports, said printing lines provided with projections and de- 20

30

pressions extending in lines lengthwise of said printing lines, and an impressing roller provided with peripheral depressions and projections arranged to coact with said first-named projections and depressions, and 35 means for moving said roller lengthwise of said printing lines.

37. In a printing mechanism, the combination of lengthwise movable supports, an impressing roller provided with peripheral 40 depressions and projections extending in lines about said roller, means for moving said roller in a path crosswise of said movable supports, said movable supports respectively provided with printing lines arranged 45 to be brought into selective cross-line arrangement at said path of said roller, said printing lines provided with projections and depressions extending in lines lengthwise of said printing lines and arranged to coact 50 with said first-named depressions and projections for action on the paper being printed.

In testimony whereof, I have hereunto signed my name in the presence of two subscribing witnesses.

ARTHUR W. MUELLER.

Witnesses:

COLEMAN AVERY,
THERESA M. SILBER.

It is hereby certified that in Letters Patent No. 1,218,105, granted March 6, 1917, upon the application of Arthur W. Mueller, of Cincinnati, Ohio, for an improvement in "Printing Mechanisms," errors appear in the printed specification requiring correction as follows: Page 2, line 74, for the word "slidably" read *slidable*; page 6, line 18, claim 9, strike out the words "below said slides"; and that the said Letters Patent should be read with these corrections therein that the same may conform to the record of the case in the Patent Office.

Signed and sealed this 3d day of April, A. D., 1917.

[SEAL.]

F. W. H. CLAY,

Acting Commissioner of Patents.

Cl. 101—19.
